UNITED STATES PATENT OFFICE

169,233

TOASTER

Philip E. Willman, St. Charles Township, Kane County, Ill., assignor to McGraw Electric Company, Elgin, Ill., a corporation of Delaware

Application January 12, 1953, Serial No. 23,107

Term of patent 14 years

(Cl. D81—10)

To all whom it may concern:

Be it known that I, Philip E. Willman, a citizen of the United States, residing in St. Charles Township, Kane County, Illinois, have invented a new, original, and ornamental Design for a Toaster, of which the following is a specification, reference being had to the accompanying drawings, forming a part thereof, in which:

Figure 1 is a view in side elevation of a toaster, showing my new design;

Figs. 2 and 3 are perspective views thereof;

Figs. 4 and 5 are sections of the outer surface taken along the lines 4—4 and 5—5 of Fig. 1 for showing surface configuration; and

Figs. 6, 7, 8 and 9 are sections of the outer surface taken along the lines 6—6, 7—7, 8—8 and 9—9 respectively of Fig. 1 for showing surface configuration.

The dominant features of my design reside in the portions shown in solid lines.

This application is a continuation-in-part of my copending prior application Serial No. D. 19,586, filed May 5, 1952.

I claim:

The ornamental design for a toaster, substantially as shown and described.

PHILIP E. WILLMAN.
